WALTER MAJESKI, OF HOBOKEN, NEW JERSEY.

REED TRIMMER.

Application filed February 28, 1925. Serial No. 12,305.

The invention relates in general to a reed clipper or trimmer of the type usually carried by a musician using a reed instrument for the purpose of trimming or reshaping the thin vibratory end of the wooden reed forming part of the mouth piece of a saxophone or similar musical instrument.

The primary object of the invention is to provide a simple form of reed clipper which can be made of small size so as to fit in the musicians' pocket, which will be light in weight and which can be used to easily and quickly trim the reed end to the exact curvature required.

Another object of the invention is to provide a form of clipper which will facilitate the locating of the reed exactly in the position required to give the requisite overlapping of the cutting edges and thus insure an extremely small but uniform amount of material cut from the reed when clipped while being held in accurately located position.

Various other objects and advantages of the invention will be in part obvious from an inspection of the accompanying drawings and in part will be more fully set forth in the following particular description of one form of device embodying my invention, and the invention also consists in certain new and novel features of construction and combination of parts hereinafter set forth and claimed.

In the accompanying drawings:

Figure 1 is a plan view of one form of instrument constituting a preferred embodiment of the invention and which view may be regarded indifferently with the showing in Figure 4 as the underside.

Figure 2 is a view in side elevation of the structure shown in Figure 1.

Figure 3 is a longitudinal sectional view taken on the line 3—3 of Figure 4, looking in the direction indicated by the arrows; and

Figure 4 is a plan view showing the obverse side of the device from the showing in Figure 1 and which view will be generally regarded as the reed receiving or top side of the instrument.

The clipper is formed primarily of a single sheet of metal, preferably steel, of any suitable outline and herein having the ornamental appearance of a musical harp.

In the following description and in the claims, parts will be identified by specific names for convenience of expression but they

are intended to be as generic in their application to similar parts as the art will permit.

The metal blank is slit within its outlines and partly cut away to provide the desired design and to form an endless main portion 10, hereinafter identified as a body portion. Extending centrally and longitudinally of the body portion and confined within its outlines is a long finger 11 integrally connected with the body portion at one end and normally extending at an angle to the plane of the body portion as indicated in Figures 2 and 3. The body portion at the free end of the finger is concaved and rounded to provide a cutting edge 12 as particularly shown in Figure 4. The free end of the finger is similarly curved to form a co-acting cutting edge 13, it being understood that when the finger 11 is moved into the plane of the body portion the cutting edges 12 and 13 abut and conform to each other.

Secured to the rear side of the finger 11 and projecting beyond the cutting edge 13 thereof is a broad finger piece 14. This finger piece overlaps one end of the body portion, as shown in Figure 3, and as the finger is moved towards the body portion into its cutting position the finger piece engages the body portion and thus limits the movement of the finger piece from moving beyond the plane of the body portion.

In such construction it is desirable to provide guide means for engaging the edge of the reed "R" and for this purpose marginal guides 15 and 16 are provided. The guide 15 is formed as a stamping pressed from the body portion in spaced relation to the cutting edge 12 and the stop 16 is conveniently formed by pressing an extension from one edge of the finger piece 14 through a slot 17 formed on the edge of the finger adjacent its cutting edge 13.

In order to limit the longitudinal advance of the reed "R" past the cutting edges 13 and 14 an end stop 18 is provided. This stop is the inturned flange of an L-shaped lever 19 rockably mounted. The lever includes a long leg 20 extending longitudinally along the back of the finger piece 14. The lever is rockably mounted on a strap 21 formed integral with the finger piece 14, extending across and fitting in a transverse groove 22 formed on the back of the leg 20 of the lever. The free end of the stop 18 is disposed opposite the body portion just in advance of the cutting edge 12 and ex-

tends through a slot 23 formed in the finger piece.

In operation and assuming that the parts are in the normal position as shown in the several figures, the operator inserts the reed "R" in position on top of the finger piece as shown in Figure 4 and moves the same laterally until the reed engages the stops 15 and 16. The reed is then advanced longitudinally while in engagement with the guides 15 and 16 until the thin end of the reed to be cut engages the stop 18.

The finger piece 14 and opposite end of the body portion are pinched together, as shown by the direction of the small arrow in Figure 3, thus clipping off a rounded portion of the end of the reed as shown in dotted line in Figure 4. With the advance of the finger the stop 16 engages the body portion and is rocked upwardly from the position shown in Figure 3 thus permitting the advance of the cutting end of the finger into shearing relation with the edge 12. Releasing tension on the parts permits the finger 11 to spring back into its normal position offset from the body portion and the instrument is again in position to have the end of the reed re-trimmed.

It is possible by engaging the stop lever with the finger engaging the finger piece 14 to rock the stop into the slot 23 and out of its reed stopping position thus permitting the advance of the reed edge to be clipped beyond the position defined by the stop. In this case a longer clip is to be taken off the reed end and the reed can be trimmed back for any desired distance. However, it is quite convenient to have the stop for it insures a minimum amount of re-trimming and the three stops 15, 16 and 18 co-act to definitely locate the reed in position as well as measure the clip cut off from the reed.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:-

1. A clipper for trimming the ends of reeds, comprising a body portion having a cutting edge, a member movable transversely relative thereto and provided with a co-acting cutting edge, said member provided with a finger piece secured to the side thereof opposite the body portion and providing an offset continuation of said member, said finger piece provided with a slot, a lever provided with an inturned end extending through the slot and spaced in advance of the cutting edge on said member to form a

stop for the end of the reed to be clipped, a strap for rockably mounting the lever in position on the finger piece to permit said stop to be removed from its position in advance of the cutting edges when the member is advanced towards the body portion. 70

2. A clipper for trimming the ends of reeds, comprising a flat body portion, a finger integral therewith and normally extending angularly from the plane of the body portion, said body portion and finger co-acting to provide a pair of shearing edges for forming a curved end to a reed, a finger piece secured to the finger and lapping the body portion, said body portion provided with a guide, said finger provided with a guide, said guides co-acting to align the reed in position relative to said shearing edges, an L-shaped lever rockably secured to the finger piece and having a laterally extending end constituting a stop for limiting the advance of the reed beyond the co-acting cutting edges, said stop spaced slightly in advance of the cutting edge of the finger and adapted to be moved into an inoperative position when moved with the finger into engagement with the body portion. 80 85 90

3. A clipper for trimming the ends of reeds, comprising a body portion provided with a cutting edge, a resilient finger provided with a co-acting cutting edge, guiding means for locating the reed transversely of its length, a stop for locating the reed longitudinally in position with the end to be clipped overlapping said co-acting cutting edges, and a finger piece constituting a continuation of the end of the finger provided with the cutting edge and offset therefrom, said finger piece lapping the body portion and constituting a stop for limiting the movement of the finger toward the body portion on its cutting movement. 95 100 105

4. A clipper for trimming the ends of reeds, comprising a flat body portion, a finger integral therewith and normally extending angularly from the plane of the body portion, said body portion and finger co-acting to provide a pair of shearing edges for forming a curved end to a reed, a finger piece secured to the finger laterally offset therefrom and lapping the body portion, said body portion provided with a guide, said finger provided with a guide, said guides co-acting to align the reed in position relative to said shearing edges. 110 115 120

5. A clipper for trimming the ends of reeds, comprising a body portion provided with a cutting edge, a resilient finger integral therewith provided with a co-acting cutting edge, guiding means for locating the reed transversely of its length and a stop carried by the resilient finger and movable therewith for locating the reed longitudinally in position with the end to be clipped overlapping said co-acting cutting edges. 125 130

6. A clipper for trimming the ends of reeds, comprising a one-piece metal blank slit within its outlines to form a body portion and a co-acting resilient finger provided at its free end with a curved cutting edge normally disposed in position offset from the plane of the body portion and adapted when pressed into the plane of the body portion to fit a co-acting cutting edge formed on the body portion, said cutting edges co-acting

to cut a curved end to a reed held between the cutting edges, and guiding means including a stamping integral with the metal blank for locating the reed in position to have its end shaped by said cutting edges. 15

Signed at New York city, in the county of New York and State of New York, this 15th day of February A. D. 1925.

WALTER MAJESKI.
